(57) **CLAIM**

The ornamental design for an electronic cigarette, as shown and described.

DESCRIPTION

FIG. 1 is a top, front, left side perspective view of an electronic cigarette, showing my new design;

FIG. 2 is a bottom, front, right side perspective view of the electronic cigarette of FIG. 1, showing my new design;

FIG. 3 is a rear view of the electronic cigarette of FIG. 1, showing my new design;

FIG. 4 is a front view of the electronic cigarette of FIG. 1, showing my new design;

FIG. 5 is a left side elevation view of the electronic cigarette of FIG. 1, showing my new design;

FIG. 6 is a right side elevation view of the electronic cigarette of FIG. 1, showing my new design;

FIG. 7 is a top plan view of the electronic cigarette of FIG. 1, showing my new design; and,

FIG. 8 is a bottom plan view of the electronic cigarette of FIG. 1, showing my new design.

The broken lines in the drawings depict portions of the electronic cigarette that form no part of the claimed design.

1 Claim, 5 Drawing Sheets
